UNITED STATES PATENT OFFICE.

HOWARD A. THOMPSON, OF EDGEWOOD BOROUGH, AND CHARLES W. FAILOR, OF PITTSBURGH, PENNSYLVANIA, ASSIGNEES TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed December 11, 1926. Serial No. 154,098.

Our invention relates to railway traffic controlling apparatus, and particularly to apparatus of the type comprising train carried governing means co-operating with 5 train controlling devices located at intervals along the trackway and controlled in accordance with traffic conditions. More particularly our present invention relates to the trackway portion of such apparatus.

10 We will describe one form of trackway apparatus embodying our invention, and will then point out the novel features thereof in claims.

15 The accompanying drawing is a diagrammatic view illustrating one form of trackway apparatus embodying our invention.

Referring to the drawing, the reference characters 1 and 1^a designate the track rails of a stretch of railway track over which 20 traffic normally moves in the direction indicated by the arrow. These rails are divided, by means of insulated joints 2, into a plurality of successive track sections A—B, B—C, etc. Each such track section is provided with 25 a source of track circuit current here shown as a track battery designated by the reference character F with an exponent corresponding to the location and connected across the rails adjacent the exit end of the section through 30 the usual impedance 9. Each track section is also provided with a track relay designated by the reference character R with an exponent corresponding to the location and connected across the rails adjacent the entrance end of the corresponding section. 35 Associated with each track relay R are a home relay and a distant relay designated by the reference characters H and D, respectively, with exponents corresponding to the 40 location. Under normal conditions, relay H is held in its energized condition by virtue of a stick circuit including its own front contact and a front contact of an adjacent track relay R. Referring particularly to 45 the apparatus located at point A, the stick circuit for relay H^A may be traced from a suitable source of energy such as a battery E^A, through wire 11, front contact 12 of relay R^A, wires 13 and 14, front contact 15 of relay H^A, wire 16, winding of relay H^A, and wires 17 and 18, back to battery E^A.

Each section is also provided with a slow acting checking relay designated by the reference character G with an appropriate

exponent and controlled in a manner which 55 will be explained hereinafter.

The circuit for relay D^A may be traced from battery E^B, through wire 11, front contact 12 of relay R^B, wires 13, 14 and 19, front contact 20 of relay H^B, wire 21, winding of relay D^A, wire 22, back contact 23 of checking relay G^A, wire 24, front contact 25 of relay H^A, and wires 26 and 18, back to battery E^B. Relay D^A is therefore energized only when relays R^B, H^B and H^A are energized and when relay G^A is deenergized.

The control of each of the remaining distant relays D is similar to that just described for relay D^A.

Each track section is also provided with a trackway signal designated by the reference character S with an exponent corresponding to the location. These signals may be of any suitable type and are here illustrated as three-indication light signals each comprising three light units 6, 7 and 8, arranged when energized to indicate stop, caution and proceed, respectively. Each signal S is controlled by the associated relays R, H and D, over circuits which will now be described.

Referring particularly to signal S^A, when relays R^A, H^A and D^A are all energized, a circuit is closed from secondary 37 of transformer T^A, through wire 41, front contact 42 of relay R^A, wire 43, front contact 44 of relay H^A, wire 45, front contact 46 of relay D^A, wire 47, unit 8 of signal S^A and wire 52, back to secondary 37 of transformer T^A. The primary 38 of transformer T^A is supplied with alternating current from secondary 39 of a transformer Q^A, the primary 40 of which is constantly supplied with alternating current from a suitable source such as an alternator M over line wires 10 and 10^a. When the circuit just traced is closed, therefore, unit 8 of signal S^A is lighted to indicate proceed. The signal S^A is also provided with a caution circuit passing from secondary 37 of transformer T^A, through wire 41, front contact 42 of relay R^A, wire 43, front contact 44 of relay H^A, wire 45, back contact 46 of relay D^A, wire 48, unit 7 of signal S^A and wire 52 back to secondary 37 of transformer T^A. When this circuit is closed, unit 7 of signal S^A is lighted to indicate caution. The stop unit 6 of signal S^A is provided with one circuit which passes from secondary 37 of trans-

former T^A , through wire 41, front contact 42 of relay R^A , wire 43, back contact 44 of relay H^A , wires 49 and 50, unit 6 of signal S^A , and wire 52 back to secondary 37 of transformer T^A . The circuit just traced is provided with a branch which passes from wire 41, through back contact 42 of relay R^A , and wire 51 to wire 50, and it therefore follows that signal S^A displays a stop indication when either of relays R^A or H^A is de-energized.

Each track section is also provided with a train controlling device here shown as a trackway inductor designated by the reference character K with an appropriate exponent and located a short distance in rear of the entrance end of the corresponding section. In the present embodiment of our invention each inductor K comprises a magnetizable core 5 provided with means responsive to traffic conditions for varying the effective reluctance of the core. The inductors K are suitable for co-operation with train carried governing means which is responsive to the effective reluctance of the cores of the inductors. In systems of this character it is customary to arrange the train governing means to give a proceed indication when passing an inductor having a comparatively high effective reluctance, and to give a stop indication on board the train when the train passes an inductor having a comparatively low effective reluctance.

The variation in the effective reluctance of the inductor cores is accomplished by providing each inductor with one or more windings which are at times shunted in response to traffic conditions. Since the operation of the train governing means depends upon the change in inductor reluctance due to the shunting effects of these windings, it is desirable to afford a check against short circuits or open circuits in the inductor windings or in the circuits associated therewith. In our present invention we accomplish this result by providing the core 5 of each inductor K with two windings 3 and 4, both of which windings are shunted when it is desirable to give a proceed indication on board the train. The windings 3 and 4 of each device K are inductively related and we utilize the transformer action between these windings to check the integrity of the circuits.

As shown in the drawing, the section to the right of point C is occupied by a train V so that track relay R^C is de-energized, thereby de-energizing relays H^C and D^C . Signal S^C therefore indicates stop. Relays R^B and H^B are energized but relay D^B is de-energized, the circuit for the latter relay being open at front contact 20 of relay H^B , and signal S^B therefore indicates caution. Relays R^A , H^A and D^A are all energized and signal S^A therefore indicates pro-

ceed. Considering now the shunting circuits for the inductors K , it will be seen from the drawing that both windings of inductor K^A are shunted by front contacts of distant relay D^A , the shunting circuit for winding 4 passing from the right-hand terminal of this winding, through wires 27 and 28, front contact 29 of relay D^A and wires 30 and 31, back to winding 4. The shunting circuit for winding 3 passing from the right-hand terminal of this winding, through wires 32 and 33, front contact 34 of relay D^A and wires 35 and 36 back to winding 3. With relay D^A energized, therefore, to shunt the windings of inductors K , the effective reluctance of the core of this inductor is comparatively high. Since relays D^B and D^C are both de-energized, the shunting circuits for inductors K^B and K^C are open and the effective reluctance of these inductors is comparatively low.

We will now assume that the train V moves out of the section to the right of point C. Relay R^C thereupon closes, but the stick circuit for relay H^C is open at its own front contact 15.

With relay H^C de-energized and relay R^C energized, alternating current is supplied to winding 4 of inductor K^C from secondary 53 of transformer P^C , the primary 54 of which is constantly supplied with alternating current from secondary 39 of transformer Q^C , the circuit for such current passing from secondary 53 of transformer P^C through wire 55, front contact 56 or relay R^C , wires 57 and 27, winding 4 of inductor K^C , wires 31 and 58, back contact 59 of relay H^C and wire 60 back to secondary 53 of transformer P^C . At the same time the checking relay G^C is connected with winding 3 of inductor K^C , the circuit passing from one terminal of winding 3, through wires 32 and 61, back contact 62 of relay H^C , wire 63, winding of relay G^C and wires 64 and 36 back to winding 3 of inductor K^C . The current supplied to winding 4 of inductor K^C induces in winding 3 an electromotive force which supplies current to relay G^C , thereby energizing that relay. As soon as front contact 66 of relay G^C closes, current from battery E^C flows through wire 11, front contact 12 of relay R^C , wires B and 65, front contact 66 of relay G^C , wire 67, winding of relay H^C , and wires 17 and 18 back to battery E^C . Relay H^C therefore becomes energized, opening its back contacts and completing, at front contact 15 thereon, the stick circuit for relay H^C by means of which the relay is subsequently maintained in its energized condition irrespective of the condition of relay G^C . The opening of back contact 62 of relay H^C interrupts the circuit for relay G^C so that the latter relay again becomes de-energized. Furthermore the opening of back contact 59 of relay H^C dis-

connects secondary .53 of transformer P^c from winding 4 of inductor K^c , so that as soon as relay H^c becomes energized, the inductor K^c is deprived of alternating current 5 and relay G^c becomes de-energized, thereby restoring the apparatus to its normal condition. Relay G^c therefore remains de-energized until the next time a train moves out of the section to the right of point C. It 10 follows that when the home relay H for the section next in advance becomes energized, relay D^c may be energized over back contact 23 of relay G^c .

It should be particularly pointed out that 15 by requiring the energization of relay G to pick up the associated home relay H when a train leaves the associated section, a positive check is made upon the windings of the adjacent inductor K , and that this check 20 insures not only that there are no breaks in the inductor windings or their associated circuits but also that there are no short circuits in the shunting circuits for either of the windings of the adjacent inductor K . 25 Such short circuit would prevent the energization of relay G and, consequently, would prevent the closing of the pick-up circuit for relay H when the train leaves the section. It will be manifest, therefore, that with 30 apparatus embodying our invention, a dangerous condition cannot arise due to a break or a short circuit in the windings of the inductor or in the circuits associated therewith, because any such defect would prevent the energization of the adjacent home 35 relay and would therefore hold at stop the signal controlled by such home relay, and would hold at caution the signal next in rear.

40 Although we have herein shown and described only one form of railway traffic controlling apparatus embodying our invention, it is understood that various changes and modifications may be made therein within 45 the scope of the appended claims without departing from the spirit and scope of our invention.

Having thus described our invention, what we claim is:

50 1. In combination, with a section of railway track, a first relay, a signal controlled by the first relay, a checking relay, a trackway device comprising a winding, means for energizing the checking relay if and only 55 if the winding is intact, a circuit for the first relay including a front contact of the checking relay, and means including a front contact of the first relay for removing the checking relay from the control of the first 60 relay.

2. In combination, a section of railway track, a relay, a signal for the section controlled by the relay, a trackway device comprising two inductively related windings, 65 means for at times shunting both said wind-

ings, means controlled by said windings and effective for a brief interval after a train leaves the section to energize the relay, and other means for subsequently maintaining the relay in its energized condition. 70

3. In combination, a section of railway track, a relay, a signal for the section controlled by the relay, a trackway device comprising two inductively related windings, 75 means for shunting both said windings when the relay is energized, means effective for a brief interval of time after a train leaves the stretch to supply alternating current to one said winding, means controlled by the electromotive force induced in the other 80 winding by such current for energizing the relay, and means for subsequently maintaining the relay in its energized condition after the windings are shunted.

4. In combination, a section of railway 85 track, a first relay, a signal controlled by the first relay, a second relay, means effective when the first relay is de-energized and operating when a train leaves the section to energize the second relay, means including a 90 front contact of the second relay for energizing the first relay, and means for subsequently maintaining the first relay in its energized condition as long as the section 95 is unoccupied.

5. In combination, a section of railway track, a first relay, a signal for the section controlled by the first relay, a trackway device comprising two inductively related windings, means controlled by the first relay for supplying alternating current to one of 100 said windings, a second relay at times connected with the other winding, means controlled by said second relay for energizing the first relay, means for subsequently removing the second relay from the control of the first relay, and means controlled by the first relay for at times shunting both said windings. 105

6. In combination, a section of railway 110 track, a track relay for such section, a home relay, a checking relay, a trackway device comprising two inductively related windings, means including a front contact of the track relay and a back contact of the home relay for supplying alternating current to one of said windings, means including a back contact of the home relay for connecting the checking relay with the other said winding, a pick-up circuit for the home relay including a front contact of said checking relay and a front contact of the track relay, a stick circuit for the home relay including its own front contact and a front contact of the track relay, and a signal for 115 said section controlled by the home relay. 120

7. In combination, a plurality of successive sections of railway track, a track relay for each section, a home relay and a distant relay for each section, a signal for each 125 130

section controlled by the associated home relay and distant relay, a trackway device for each section comprising two inductively related windings, a checking relay for each section, means for supplying alternating current to one winding of each trackway device when the adjacent track relay is energized and when the adjacent home relay is de-energized, means for connecting 10 each checking relay with the remaining winding of the adjacent trackway device when the home relay associated with such checking relay is de-energized, a pick-up circuit for each home relay including a front 15 contact of the associated checking relay and a front contact of the associated track relay, a stick circuit for each home relay including its own front contact and a front contact of the associated track relay, a circuit 20 for each distant relay including front contacts of the associated home relay and the home relay for the section next in advance and a back contact of the associated checking relay, and means controlled by each distant relay for shunting both windings of 25 the associated trackway device.

8. In combination with a section of railway track, a first relay, a signal controlled by the first relay, a second relay, means for 30 at times closing the second relay for a brief interval of time, a pickup circuit for the first relay controlled by the second relay, and a stick circuit for the first relay.

9. In combination with a section of rail-

way track, a first relay, a signal controlled 35 by the first relay, a second relay, means for at times closing the second relay for a brief interval of time, a pickup circuit for the first relay controlled by the second relay, and means for subsequently maintaining 40 the first relay in its energized condition irrespective of the condition of the first relay.

10. In combination, a section of railway track, a first relay, a signal controlled by 45 the first relay, a second relay, a trackway device comprising a winding, means for at times energizing the second relay if and only if the winding is intact, a pickup circuit for the first relay controlled by the 50 second relay, and a stick circuit for the first relay.

11. In combination, a section of railway track, a home relay arranged to be de-energized when the section is occupied, a signal 55 controlled by the home relay, a checking relay, a trackway device comprising a winding, means including a back contact of the home relay for energizing the checking relay when a train leaves the section if and only if said winding is intact, a pickup circuit for said home relay including a front contact of the checking relay, and a stick circuit for the home relay.

In testimony whereof we affix our signatures.
